UNITED STATES PATENT OFFICE.

ALONSO D. PERALTA, OF GUATEMALA CITY, GUATEMALA.

HOSE-SUPPORTER.

1,348,045.

Specification of Letters Patent. Patented July 27, 1920.

Application filed April 22, 1919. Serial No. 291,830.

To all whom it may concern:

Be it known that I, ALONSO D. PERALTA, a citizen of the Republic of Guatemala, and a resident of Guatemala City, Republic of 5 Guatemala, have invented a new and Improved Hose-Supporter, of which the following is a description.

My invention relates to garment supporters, and more particularly relates to a 10 device adapted for use as a hose or sock supporter although not limited in all its phases to that particular use.

The general object of my invention is to provide a supporter of the indicated character 15 improved in various particulars especially having in view the effective gripping of the supported garment and convenience in applying and detaching the supporter.

The above and other objects as will appear 20 are attained by a supporter presenting a suspender end or ends in looped form through or into which a portion of the hose for example may be passed, together with a slide into which the loop with the portion 25 of the hose therein may be drawn and then securely clamped.

In the preferred form the device embodies a pair of suspender ends such as referred to and these are carried by a suspension 30 element equipped with similar gripping means whereby to fasten the supporter to the drawers or other undergarment of the wearer.

Reference is to be had to the accompanying 35 drawings forming a part of this specification, it being understood that the drawings are merely illustrative of one example of the invention.

Figure 1 is a front view of a supporter 40 embodying my invention;

Fig. 2 is a portion of one of the suspender ends indicating the manner of engaging the loop with the hose;

Fig. 3 is a view similar to Fig. 2 indicating 45 the position of the parts when the loop with the garment portion therein has been drawn into the slide and clamped therein;

Fig. 4 is a longitudinal vertical section of one of the slides and the adjacent portion of 50 the loop the view including a portion of the hose.

In the illustrated example two suspender ends 10 are integral with each other and formed by an endless flexible element 11, and slides 12 are provided on said ends 10. The terminals of said suspender ends pre-

sent loops 13 through which a portion *a* such as the edge portion of a hose or sock *A* may be passed. The arrangement is such that the loop 13 with the part *a* therein and the adjacent portion of the garment may be drawn into the slide 12 or rather the slide may be moved forwardly on an end 10 over the loop 13 and the engaged portion of the garment.

Clamping means is provided on each slide 12 to firmly grip the loop and the engaged portion of the garment when within the slide.

In the illustrated example I have shown a U-shaped spring 12^a in the slide 70 and the bend of said spring lies at the interior of the curved, closed upper end of the slide as best seen in Fig. 4. Said closed end has holes therethrough for the passage of

the two strands of the flexible element 11, so 75 that the slide may be freely moved forward or back on the strands to or from the end of the loop 13. One arm 12^b of the U-spring

12^a is free to be flexed under the pressure of an L-shaped lever 12^c pivoted to rock in a 80 slot 12^d in the slide and having its foot or L-member 12^e adapted to bear against the arm 12^b of the spring to clamp the latter tightly onto the portion of the garment and the loop.

Associated with the flexible element 11 having the described features is a suspension element 14 which also in practice is in the form of an endless strand and is equipped with a slide 12 in all respects the same as 90

those previously described. Said element 14 presents an end loop 13^a corresponding with the loops 13 into which a portion of the drawers or other undergarment of the wearer may be passed and then drawn with 95 the loop into the slide 12, whereby the ends 10 may be suspended in position to engage a sock at opposite sides of the leg.

In order to detachably connect the suspension element 14 with the element 11 between the ends of the latter, I provide a clasp comprising a member 16 on the element 11 and a member 17 hung on the lower end of the element 14. One of said members (16 in the illustrated example) has a 100 stud 18 thereon which is receivable in a key-hole slot 19 in the other member (17).

I would state in conclusion that while the illustrated example constitutes a practical embodiment of my invention, I do not limit 110 myself strictly to the mechanical details herein illustrated, since manifestly the same

can be considerably varied without departure from the spirit of the invention as defined in the appended claims.

Having thus described my invention, I claim as new, and desire to secure by Letters Patent:

1. A device of the class described including a suspender end presenting separate side members formed into a loop into which a portion of a garment may be passed, and a slide movable on said side members and into which said loop may be drawn with the engaged portion of the garment, said slide having swingable clamp means to grip the received loop and garment portion.
- 10 2. A device of the class described including a flexible element in looped form adapted to receive a garment portion to be gripped, a slide carried on said loop and

movable to and from the end thereof, so that the loop end with the garment portion may pass into the slide, and clamp means carried by and movable on said slide to and from clamping positions, said means being adapted to clamp the loop and the engaged portion of the garment to said slide.

3. A device of the class described including a flexible element presenting a loop into which a portion of a garment may be passed, a slide carried by said element and presenting a front and back spaced from each other and between which the portion of a garment and said loop may be passed, and means on the slide to clamp the loop and said portion of the garment between said front and back.

ALONSO D. PERALTA.
